UNITED STATES PATENT OFFICE.

KARL MAIER, OF STUTTGART, GERMANY, ASSIGNOR TO THE FIRM OF UNION SPECIAL MASCHINENFABRIK G. M. B. H., OF STUTTGART, GERMANY.

MULTINEEDLE SEWING-MACHINE.

1,098,814.

Specification of Letters Patent.

Patented June 2, 1914.

Application filed December 6, 1911. Serial No. 664,260.

To all whom it may concern:

Be it known that I, KARL MAIER, a citizen of the German Empire, residing at Stuttgart, in the Kingdom of Wurttemberg, Empire of Germany, have invented certain new and useful Improvements in Multineedle Sewing-Machines; and I do hereby declare the following to be a full, clear, and exact description of the invention, such as will enable others skilled in the art to which it appertains to make and use the same.

In multi-needle sewing machines with a looper, the latter works in conjunction with the needles and takes the loops of the needle thread with it on its return movement, so that they come into a somewhat inclined position. For this reason it has hitherto been necessary to arrange the needles so far apart that they cannot enter the loops drawn obliquely toward the adjacent needles, and this therefore necessitated a certain width of seam. This disadvantage is avoided in the present invention by a member being provided which regulates the position of the needle thread loops on the return of the looper, and holds them in such a way that even when the needles are placed close together, they cannot enter the loops of the adjacent needles but the needle loops are held apart or in a vertical position spaced apart. For this object a loop-holder is provided, which may be shaped like a comb and the projections of which pass between the needles and in this way regulate the position of the loops. The distance between the needles is thus no longer dependent on the inclined position of the loops of the thread, and it is possible to obtain rows of stitches with small intervals between them. The loop-holder is also suitably controlled by the oscillating operating member of the ordinary looper or gripper and it may be directly attached to one of these parts. The loop-holder may also be displaced laterally with reference to the needles and also vertically to the gripper and the needle plate.

The invention will now be more particularly described with reference to the accompanying drawings, in which a form of construction is shown by way of example.

Figure 1 is a front view of the stitch-forming devices in question; and Fig. 2, an end view of the same; Figs. 3 and 4 show different positions of the stitch-forming de-

vices to those shown in Figs. 1 and 2; Fig. 5 illustrates in front view the action of the loop-holder.

The stitch-forming devices consist, as usual, of needles *a* carrying threads *b* which remain behind in the form of loops, on the return of the needles. The ordinary looper *c*, which receives a reciprocating movement from the driving gear of the machine by means of a push-rod *d* and is caused to have a rocking movement by means of the swinging frame *h*, then serves for locking the loops. Now in order to prevent the loops of the needle threads being brought into too inclined a position by the looper *c* on its return movement, a loop-holder *e* is provided, which is formed, for instance, as a comb and the projections *f* of which pass between the adjacent loops of the needle thread (Fig. 5), so that these loops are held. The loop-holder *e* is suitably operated from one of the oscillating parts of the mechanism for operating the looper, for instance, from its frame *h*, so that it is set in swinging motion with the latter and thus enters between the loops. It is also mounted on the shaft *g* of the frame *h* which is displaceably mounted in the machine frame. In order to allow of its adjustment relatively to the frame *h*, the loop-holder *e* is also vertically adjustable by means of a screw *i* and a slot on the end of the shaft *g*, the screw *i* passing through an elongated slot *k* of the loop-holder *e*. By turning the shaft a further adjustment at right angles to the needle movement may thus be obtained.

I declare that what I claim is:

1. In a sewing machine having a plurality of spaced needles, and a looper coöperating therewith to form stitches, a movable loop-holder having a plurality of projections adapted to extend between the needles to hold the needle loops apart, and means for oscillating said loop-holder in a direction transverse to the direction of the movement of the looper.

2. In a sewing machine having a plurality of spaced needles, and a looper coöperating therewith to form stitches, a movable loop-holder, having a plurality of projections adapted to extend between the needles to hold the needle loops apart, and means for oscillating said loop-holder in a direction transverse to the direction of the movement
